BOX STRUCTURE

Neil P. Van Wingen, Grand Rapids, Mich., assignor to American Box Board Company, Grand Rapids, Mich., a corporation of Michigan

Application September 20, 1937, Serial No. 164,682

10 Claims. (Cl. 229—33)

This invention relates to a box structure which may be very readily manufactured at low cost from paperboard stock, without appreciable waste of material, and wherein the ends of the box are very strongly reinforced. Such box is adapted to be used in the carrying and transportation of relatively heavy articles such as bottled goods. The box is carried by the insertion of the hands through hand hole openings in the ends of the box so that such ends are subjected to heavy strain and wear and require strengthening and reinforcement more than other portions of the box. Furthermore, the box should be accessible for placing the contents carried therein and their removal therefrom, and in the present invention a cover means in two parts hinged to the sides of the box and turning inwardly toward each other to close the box is provided from the substantially rectangular blank of paperboard material that supplies the remaining parts of the box including the end reinforcing structure. The hand holes are further strengthened and reinforced and the upper edge portions thereof made smooth and widened in area by very simple constructive detail. All of these features of construction combine to produce a box of very practical worth.

An understanding of the invention may be had from the following description, taken in connection with the accompanying drawings, in which, Fig. 1 is a plan of the blank which is cut from a rectangular piece of paperboard stock and which may be folded and shaped into the completed box structure.

Fig. 2 is a perspective view of the box of my invention, the upper closure being thrown open.

Fig. 3 is a partial transverse section and perspective of the box, the upper side being closed.

Fig. 4 is a fragmentary horizontal section at one end of the box, and

Fig. 5 is a longitudinal vertical section at one end of the box, the upper end being closed.

Like reference characters refer to like parts in the different figures of the drawings.

The sheet of paperboard stock from which the box is made is of substantially rectangular form, there being removed or cut away therefrom the rectangular corner portions shown at 1, these being the only parts of the sheet which is waste. A central area of the blank indicated at 2 will 50 comprise the bottom of the box. The blank is scored transversely at spaced-apart points entirely across the same, as at 3, and longitudinally at spaced-apart points, at 4, such scorings providing the boundaries for the bottom section 2. 55 In alignment with the ends of the bottom section

2 are end sections 5 having the same width as the bottom 2. In the outer edge of each of the end sections 5 an inwardly extending slot 6 is cut and in the body of each end section 5 a flap 7 is cut at three sides and remains integral with the blank at its fourth side at which it is scored, as at 8, for turning the flap inwardly, as will be later described, to reinforce and strengthen the hand holes, one at each end of the completed box.

From each corner where the scorings 3 and 4 cross each other a diagonal cut 9 is made for a short distance and then is continued in the cuts shown at 10, parallel to and spaced a short distance from the longitudinal scorings 4. The cuts 15 at 10 are in alignment with one side of the recesses or rectangular notches at 11 at each corner of the blank. Such cuts provide reinforcing sections 11 one at each side edge of each of the end sections 5. Each of the reinforcing sections 20 is slotted at its outer edge at 12, and between said slots and the cuts at 10 parts are cut away to make holes 13 which are of a shape that the hands of the man handling the box may be readily inserted therethrough. The notches 12 and 25 the holes 13 are so located in the sections 11 that when said sections 11 one at each side of an end section 5 are turned inwardly and overlap each other, the holes 13 come into conjunction with each other and directly in conjunction with the 30 flap 7 which may be inserted through the holes at 13 and bent around and upwardly toward the notches 6 and 12, which are brought into alignment by such folding, and the flap stapled in place as shown in Fig. 5, thereby permanently 35 connecting flaps 7, the end sections 5, and the reinforcing sections 11.

Each part of the blank which extends outwardly beyond the scorings 3 and within the cuts 10 is scored at 14 and 15 parallel to the scorings 40 3, and notches or slots 16 are cut inwardly in the ends thereof in alignment with the scorings 14 and of a depth reaching to the scorings at 6. Also, at the outer edges of the blank and in alignment with the scorings 4 other notches or 45 slots 17 are cut extending from the edges of the blank to the scorings at 15. There are thereby defined between the parallel scorings 3 and 14 and the scorings 4 two sides 18 for the box; while between the parallel scorings 14 and 15 and said 50 scorings 4 are two top sections 19. There are also provided flaps 20 one at each end of each side 18, and flaps 21 one at each end of each top section 19. There are further provided between the slots at 17 and the scorings at 15 small sub- 55

stantially square flaps 22 in alinement with which and between the same are relatively narrow flaps 23 outwardly beyond the scorings at 15.

With this blank construction the reinforcing flaps 11 may be bent inwardly against the inner sides of the ends 5, one overlapping the other as shown in Fig. 4 and the hand hole flaps at 7 bent inwardly through the openings at 13 and stapled in place as previously described. The 10 end structure may be then bent upwardly about the scorings at 4 and the sides 18 upwardly about the lower scorings 3, the flaps 20 turned inwardly toward each other to overlap the ends 5, as shown in Fig. 2, whereupon said flaps 20 and the 15 ends 5 with the reinforcing section 11 are stapled together. The flaps 22 are bent at right-angles to the flaps 21 and then the flaps 21 and 23 turned at right-angles to the plane of the top sections 19, the end flaps 22 coming inside of the 20 end portions of the flaps 23 and being stapled thereto. This provides two top sections hinged to the sides 18 of the box at the scorings 14 and adapted to be turned inwardly, the slots at 6 and 12 in the end sections 5 and the end reinforcing 25 members 11 receiving the inturned flaps 23 and the reinforcing corner portions 22 thereof, while the flaps 21 lie outside of the upper edge portions of the ends of the box (see Fig. 5).

With this construction of box the ends are very 30 strongly reinforced. The holes through which the hands of those handling the boxes are inserted, at 13, are strengthened and reinforced by the inturned and stapled flap sections 7, while the upper edges of said holes are rounded and 35 broadened so as to make a smoother and wider bearing surface to come against the palms of the hand in lifting the box and its contents. The upper side of the box may be opened fully for placing bottled goods or the like within, and then 40 the box closed by turning the top sections to closed position as in Fig. 3, whereupon the box may then be sealed along the dividing line between the two top sections if desired. If for any 45 reason it appears desirable to strengthen the box bottom, this construction of box is one which is very easily reinforced by merely cutting a piece of paperboard stock to the right rectangular size and placing it within and against the upper side of the bottom of the box, connecting it in place if wanted; and, of course, either end or side flaps 50 or both could be provided to the reinforcing bottom and stapled in place. However, such reinforcement is no part of the present invention and is mentioned only to show the adaptability of the 55 box which I have invented to such reinforcement if it should be wanted.

The box structure is one of an economical design, the blanks are cut with dies very rapidly, 60 large quantity production may be had, the blanks may be shipped in flat form and very quickly and easily shaped into the completed box requiring only the stapling of the flaps 7, 20, and 22 after the blank has been bent along the scored lines to the proper positions.

The invention is defined in the appended claims and is to be considered comprehensive of all forms of structure coming within their scope.

I claim:

70 1. A box comprising a bottom, vertical sides and ends, said ends having reinforcing members folded inwardly, one from each vertical edge thereof and overlapping each other and permanently connected to said ends, and each side having projecting flaps extending inwardly over the 75

ends and permanently secured thereto, as specified.

2. A construction containing the elements in combination defined in claim 1, said ends having flaps cut therefrom at three sides and said reinforcing sections having openings which are brought into conjunction when the reinforcing sections are folded into place, said flaps extending through said openings and being bent around the upper edge portions thereof and against the inner side of the innermost reinforcing section, and means connecting said flaps, reinforcing sections and end members. 5

3. A box of the class described made from a single piece of paperboard having a horizontal bottom, vertical sides turned upwardly from the side edges of said bottom, vertical ends turned upwardly from the ends of said bottom, reinforcing sections one at each side edge of each vertical end and turned inwardly and overlapping 15 each other at the inner side of each end, flaps extending from each end of each vertical side and overlapping said ends, and staples extending through said flaps, ends and reinforcing sections, as specified. 20

4. A construction containing the elements in combination defined in claim 3, said ends and reinforcing sections at their upper edges and intermediate their side edges having vertical slots cut downwardly therein for a short distance, said 30 slots coming into alining conjunction when the reinforcing sections are folded one against the other and both at the inner sides of the ends. 25

5. A shipping case made from a blank of flat material, having a bottom, two sides, and two top 35 sections in alinement in said blank, and having ends one at each end of the bottom in alinement therewith and further provided with reinforcing sections one at each edge of each end, said blank being scored transversely for its full width at each 40 side edge of the bottom and scored longitudinally for its full length at each end of the bottom, said blank being cut starting at each point where said longitudinal and transverse scorings cross each other, said cut extending outwardly at an angle to 45 the scorings for a short distance and then parallel to said longitudinal scorings whereby the blank may be folded upon said scorings to provide a bottom, vertical sides, vertical ends, inwardly foldable reinforcing sections, one at each 50 vertical side edge of each end adapted to overlap each other and lie against the inner side of the end to which connected, and further providing an end flap one at each end of each vertical side adapted to be turned inwardly at the outer side 55 of each end of the box and extend vertically to the upper edges of the box, as specified.

6. A shipping case made from a blank of flat material, having a bottom, two sides and two top sections in longitudinal alinement in said blank 60 and having ends, one at each end of the bottom and further provided with reinforcing sections one at each edge of each end, said blank being scored transversely at each side edge of the bottom and scored longitudinally at each end of the 65 bottom, said blank being cut starting at each point where said longitudinal and transverse scorings cross each other, said cuts extending outwardly at an angle to the scorings for a short distance and then parallel to said longitudinal 70 scorings whereby the blank may be folded upon said scorings to provide the bottom, vertical sides, vertical ends and two inwardly foldable reinforcing sections for each end adapted to lie over each other against the inner side of the end to 75

which connected, said blank being further transversely scored between the upper edge of each vertical side and a top section, said scorings extending between the longitudinal scorings of the blank and there being a transverse slot at the end of each of said last mentioned transverse scorings extending outwardly to the adjacent cut, and said blank being further transversely scored a short distance inwardly from each end thereof and having slots in each end of the blank in alinement with said longitudinal scorings extending to said last-mentioned transverse scorings, substantially as and for the purposes described.

7. A construction containing the elements in combination defined in claim 6, each of said ends and each of said end reinforcing sections having a slot in its outer edge substantially midway between its side edges, all of said slots in an end and two cooperating reinforcing sections coming into alining conjunction when said reinforcing sections are inwardly folded to overlap each other and lie against the inner side of the end to which attached.

8. A box made from a blank of flat material comprising, a bottom, vertical sides and ends, each end having reinforcing members integrally connected therewith and folded inwardly to overlap each other and lie against the inner side of

its associated end, and means integral with each vertical side adapted to be folded inwardly toward each other at the outer sides of said ends whereby securing means may be passed through said means and through the ends and said reinforcing members to permanently connect them together.

9. A box of the class described made from a single blank of flat material having a horizontal bottom, integrally connected vertical sides turned upwardly from the side edges of said bottom, integrally connected vertical ends turned upwardly from the end edges of said bottom, reinforcing sections integrally connected, one at each vertical side edge of each end and turned inwardly and overlapping each other at the inner side of each end and flaps integrally connected with and located one at each end of each of said sides, and turned inwardly toward each other over the outer sides of said ends, as and for the purposes specified.

10. A box comprising a bottom, vertical sides and ends, said ends having reinforcing members integral therewith and folded inwardly one at each vertical edge of each end and overlapping each other, and means for connecting the sides, ends and reinforcing members together.

NEIL P. VAN WINGEN.
